DISPLAY DEVICE

Robert F. Andre, Cleveland Heights, Ohio

Application November 14, 1952, Serial No. 22,294

Term of patent 3½ years

(Cl. D80—1)

To all whom it may concern:

Be it known that I, Robert F. Andre, a citizen of the United States, residing at Cleveland Heights, county of Cuyahoga, and State of Ohio, have invented a new, original, and ornamental Design for a Display Device, of which the following is a specification, reference being had to the accompanying drawings, forming a part hereof.

Fig. 1 is a front view of a display device, showing my new design;

Fig. 2 is a bottom plan view; and

Fig. 3 is a rear view in perspective thereof.

I claim:

The ornamental design for a display device, substantially as shown.

ROBERT F. ANDRE.
